SHIRRING DEVICE

Charles Seaman, Jamaica Estates, N. Y.

Application June 27, 1935, Serial No. 28,594

16 Claims. (Cl. 112—134)

This invention relates to sewing machines and more particularly to a device or attachment for making and stitching shirring or ruffling onto a base material.

5 An object of the invention is to provide a device for shirring at spaced intervals so as to make a trimming of attractive design.

Another object is to provide means for automatically interrupting or modifying the shirring operation at predetermined intervals.

10 Another object is to provide a trimming having spaced shirring or puckles.

Another object is to provide a shirring having non-uniform characteristics.

15 Another object is to provide a shirring, the characteristics of which are varied at regular intervals.

Another object is to provide a device for making and attaching a shirring of the above type with a single row of stitches.

20 Another object is to provide a simple, efficient and dependable device for the above purposes.

Various other objects and advantages will be apparent as the nature of the invention is more 25 fully disclosed.

Although the novel features which are believed to be characteristic of this invention will be pointed out more in detail in the claims appended hereto, the broad aspects of the invention will be better understood by referring to the following description taken in connection with the accompanying drawings in which:

Figure 1 is a front elevation of a sewing machine embodying the present invention.

35 Figure 2 is a top plan view thereof, partly broken away to show the shirring attachment.

Figure 3 is a rear elevation of a portion of the sewing machine showing the intermittent drive.

40 Figure 4 is an end elevation of the machine showing the intermittent drive.

Figure 5 is a section taken on the line 5—5 of Figure 4.

Figure 6 is a perspective view illustrating the shirring attachment.

45 Figure 7 is an end elevation of the machine partly in section showing the shirring attachment and presser foot operating mechanism.

Figure 8 is a plan view of one type of shirring produced by the present device.

50 Figure 9 is a section taken on the line 9—9 of Figure 8.

Figures 10 and 11 are plan views showing different forms of shirring which can be produced by the present device.

Figure 12 is a side elevation, partly in section, of one of the guide mechanisms.

Figure 13 is a partial end elevation of a modified form of the cam.

In the specification and in the claims certain specific terms have been used for convenience in referring to the various details of the invention. These terms, however, are to be given as broad an interpretation as the state of the art will permit.

Referring to the drawings more in detail, the 10 invention is shown as embodied in a sewing machine comprising a head 1, having a needle bar 2, which is reciprocated by suitable driving means, such as a pulley 3, driven by a belt (not shown). The needle bar 2 is adapted to carry 15 a needle 4 by which the sewing is effected in a well-known manner. The head 1 also carries a presser foot bar 5 having a presser foot 6 adapted to hold the material in engagement with a set of feed dogs 7 which are mounted below a base 20 plate 8 and extend through an aperture 9 therein. The feed dogs 7 may be operated by any suitable means to intermittently engage the material and feed the same past the needle for stitching. The presser foot bar 5 carries an arm 25 12 which is adapted to be engaged by a cam lever 13 for raising the presser foot bar from the work when it is desired to release the work, for example, to adjust the position thereof in the machine. The cam lever 13 may be pivoted to 30 a portion of the head 1 and may have a handle 14 located in a position readily accessible to the operator of the machine. The upper end of the presser foot bar 5 may be journaled in a sleeve 15, which may be threaded into the head 1, and 35 serves as an adjustable shoulder against which a spring 16 is seated. The spring 16 is coiled around the presser foot bar 5 between the sleeve 15 and the arm 12 and serves to hold the presser 40 foot 6 against the material when the lever 13 is released.

In order to operate the presser foot bar without removing the hands from the material, a knee-operating means is provided, comprising a lever 20 which is pivoted to the back of the head 45 1, as at 21, and is connected at one end to a link 22 which is, in turn, pivoted to the arm 12, as by screw 23. The link 22 may be provided with an elongated slot 24, engaging a pin 25, carried by a lug 26, secured to the lever 20. The elongated slot 24 provides a sufficient amount of lost motion to permit the presser foot bar 5 to be 50 elevated by the lever 13 without moving the lever 20. The lever 20 is operated by a link 27 which is pivotally connected to a lever 28. The 55

lever 28 is adapted to be operated by suitable mechanism (not shown) responsive to knee pressure.

It is to be understood that the mechanism thus far described is of standard construction and only so much thereof has been shown as is necessary for a complete understanding of the present invention.

The stirring attachment comprises a plate 32, which is adapted to be secured to the base plate 8 of the machine, as by screws 33 (Figures 2, 6 and 7). The plate 32 carries a block 34 to which a plurality of bars 35 and 36 are secured. These bars may be joined at the free ends by a cross-bar 37 to form a comparatively rigid framework. A resilient lever 38 may be secured to the bar 35, as by a screw 39. One end of this lever may be bent downwardly to form an auxiliary presser foot 40 having a center notch 41 through which the needle 4 is adapted to pass. The other end of the lever 38 may extend over the bar 36 and may provide a handle to facilitate adjustment thereof. A lever 42 may also be pivoted to the bar 35 and may be adapted, when rotated in the direction of the arrow (Figure 6), to press against the under surface of the lever 38 for raising the auxiliary presser foot 40. A guide member 45 comprising a plate 46, one side of which is bent over to form a flange 47, may be secured to a bar 48 which is slidably held in the block 34, as by an adjustment screw 49. In addition to serving as a means for adjusting the guide member 45, the bar 48 cooperates with the bars 35 and 36 to form a tensioning gate for the stirring material. A wire 50 may be secured to the bar 36 or to the guide member 45 and may extend at an angle thereto for guiding the stirring material to the guide member. The wire 50 may be of sufficient length to receive stirring material of varying widths and to permit the shifting of the same relative to the feeding means of the sewing machine by adjustment of the guide member 45. The auxiliary presser foot 40 may also have mounted thereon an edge folder 51 of the usual construction and arranged to normally align with the needle 4 and the main presser foot 6.

To permit adjustment of the presser foot 6, the top of the presser foot bar 5 may be tapped, as at 60, and may receive a threaded pin 61 carried by a hand nut 62. The presser foot bar is free to move vertically within the sleeve 15 and the hand nut 62 provides a stop which bears against the top of the sleeve 15 for determining the lower position of the presser foot 6. As the hand nut 62 is rotated, the presser foot bar 5 is adjusted upwardly or downwardly within the sleeve 15.

The intermittent driving mechanism comprises a cam wheel 65 carrying cams 66 and a friction drum 67. The cam wheel may be journaled on a shaft 68, which is supported by a bracket 69, and may be held by a spring 70 in frictional engagement with a stop nut 71. It is to be understood, however, that other suitable bearing supports may be provided for the cam wheel 65, if desired. The bracket 69 may be secured by a screw 72 to the head 1 of the sewing machine. The arrangement is such that the screw 72 is adapted to be inserted in a tapped hole 73 which is normally made in the sewing machine head whereby the device may be attached to the head without drilling or otherwise injuring the same.

75 A cam disk 74 may be provided with cams 75

similar to the cams 66 and may be adjustably secured to the cam wheel 65, as by a screw 76, cooperating with an elongated slot 77 in said cam wheel. The arrangement of the cams 75 and 66 is such that rotational movement of the cam disk 74 with respect to the cam wheel 65 causes the effective length of the cam surface to be varied.

For operating the cam wheel, there is provided an arm 80 which is journaled about the shaft 68 and is provided with a slot 81 in which a link 82 is adjustably pivoted, as by means of an adjustable screw 83. The link 82 is provided with an eccentric 84, which is secured to the hub 85 of the driving pulley 3 of the machine, in such manner that the link 82 is caused to reciprocate vertically as the pulley 3 is rotated and to cause corresponding movement of the arm 80.

The arm 80 is connected to the cam wheel 65 by means of friction ratchet mechanism comprising friction driving members 86 made of suitable friction material, such as a carbon composition, and having a recess or channel 87 adapted to seat over the friction drum 67, but having sufficient clearance with respect thereto to permit the drum to be driven in one direction in the manner hereinafter specified. The friction driving members 86 rest at their inner ends against shoulders 88 formed on the arm 80 and are held against said shoulders and against the friction drum 67 by means of springs 89 which extend between the members 86 and ears 90 associated with the arm 80.

For preventing reverse movement of the cam wheel 65, a brake is provided comprising a friction member 91 formed preferably of material 35 similar to that of the members 86. Said member 91 is provided with a channel 92 adapted to seat over the friction drum 67 and extends through an aperture 93 in a guide plate 94 which is secured to the bracket 69, as by a screw 95. A spring 96 may extend between the friction member 91 and an ear 97 formed on the guide plate 94 to hold the friction member 91 in a position to prevent clockwise movement of the drum 67, as viewed in Figure 4, but to permit movement of the drum 67 in the opposite direction as indicated by the arrow in Figure 4.

The arrangement of the driving mechanism above described is such that on each downward stroke of the arm 80 the members 86 frictionally engage the friction drum 67 and cause rotation thereof in a counter-clockwise direction, the drum slipping in the member 91. Upon each upward stroke of the arm 80, the member 91 holds the drum 67 against reverse movement and the friction members 86 are caused to slide thereabout. The construction, in effect, provides a one way clutch which permits the arm 80, by reciprocating rapidly, to cause a slow rotational movement of the cam wheel 65 in one direction only. The speed of rotation of the cam wheel is adjusted by varying the position of the screw 83 in the slot 81. When the screw 83 is shifted further from the center about which the arm 80 rotates, the angular throw of the arm 80 is made smaller and the angular movement of the cam wheel 65 at each stroke of the arm 80 is correspondingly less. When the screw 83 is shifted nearer said center, a correspondingly faster rotation of the cam wheel is obtained.

The cams 75 and 66 cooperate with a roller 100 carried by an arm 101 which is pivoted as at 102 to a bracket 103, secured to the bracket 69 by suitable means, such as a screw 104. Obviously, the bracket 103 and the guide plate 94 may be 75

formed integrally with the bracket 69, if desired. The arm 101 slidably engages a collar 106, which is held between the stops 107 on the link 27, by which the position of the presser foot bar 5 is adjusted. The point of attachment of the arm 101 to the link 27 may be adjusted by varying the position of the stops 107. If desired, a dowel 108 may be secured to the guide plate 94 in a position to engage a hole 109 which is usually formed in the base plate of the sewing machine. The position of the dowel thus assists the screw 72 in rigidly securing the attachment in place.

A guard 110 may be secured over the bars 35, 36 and 48, as by screws 111 engaging the block 34. This guard is adapted to prevent the operator from coming in contact with the shirring material and interfering with the feed thereof. A guide wire 112, having adjustable stop members 113, may be secured to the guard 110 for guiding the shirring material thereto.

In the operation of this device, the shirring material 120 may be fed from a roll 121, which is supported on a suitable bracket 122, over the guide wire 112, under the guard 110, under and over alternate bars 35, 48 and 36 of the tensioning gate, around the wire 50, through the guide member 45, under the auxiliary presser foot 40, and into engagement with the feed dogs 7. The shirring material 120 is thus positively fed by the feed dogs 7 whenever the machine is operated, being held in feeding position by means of the auxiliary presser foot 40. In order to thread this material through the machine, the presser foot 40 may be raised by operating the lever 42. During operation, however, this lever is caused to release the presser foot 40 and permit the same to hold the material into feeding position.

The base material 123 is fed to the needle over the presser foot 40 and under the presser foot 6, whereby the feed thereof is determined by pressure exerted by the presser foot 6. If the edge of the base material is to be folded to receive the stitching, the edge may be passed through the edge folder 51 which aligns with the needle 4 so that the edges are folded and fed to the needle in condition for stitching.

If the shirring material 120 is to be applied to a position other than the edge of the base material 123, the latter may be fed over the edge folder 51 and may extend on both sides thereof a suitable amount to bring the desired portion into the path of the needle.

When the material is fed to the machine in the manner above described and the presser foot 6 is elevated above the base material a sufficient amount so that a full feed is not obtained, the shirring material is fed at a faster rate than the base material and is caused to pucker up or gather in folds or shirring at the point of stitching. The shirring material is stitched in this condition, whereby a single row of stitches holds the material in shirred condition and attaches the same to the base material.

The relative rates of feed, and consequently the amount of puckering or gathering of the shirring material, may be controlled by varying the pressure of the presser foot 6. With the presser foot 6 fully raised, a maximum slippage takes place between the base material and the feed dogs, whereby the greatest shirring effect is obtained. As the presser foot 6 is lowered and exerts a greater pressure on the base material, less slippage takes place. Hence, less shirring effect is obtained. When the presser foot 6 is in its lowest position, the feed dogs 7 feed the base

material and the shirring material at the same speed and no shirring effect is obtained. In Figure 13 there is shown a cam wheel 65 and a cam 66 which may be used when it is desired to vary the pressure of the presser foot on the material.

As the machine is operated, the cam wheel 65 is caused to rotate continuously at a substantially constant speed. The cams 66 and 75 alternately raise and lower the roller 100 and, through the arm 101, cause similar movement of the rod link, the lever 20, and the presser foot bar 5. The presser foot 6 is thus intermittently raised and lowered as the machine is operated.

When the presser foot is lowered, the shirring material 120 and the base material 123 are fed at equal speeds and no shirring takes place, thereby producing a flat portion 131 (Figure 8). When the presser foot is raised, shirring takes place to produce a shirred portion 130. This continues at regular intervals to produce an intermittent shirred trimming as illustrated in Figure 8. The relative spacing of the shirred portion 130 and the flat portion 131 can be adjusted by varying the speed of rotation of the cam wheel, as by changing the point of connection of the link 82 to the arm 80. When the cam wheel is speeded up, shirring takes place at shorter intervals and the shirred portions are spaced closer together as indicated by shirred portions 132 and flat portions 133 in Figure 10. It is obvious that, by varying the point of adjustment of the link 82 to the arm 80, any desired spacing can be obtained.

In order to vary the ratio between the shirred and unshirred portions, the length of the cams may be adjusted by loosening the screw 76 and rotating the cam disk 74 with respect to the cam wheel 65. The greater the cam length, the greater the relative time that the presser foot is raised and a greater relative amount of shirring is obtained.

It is also possible to vary the characteristics of the shirring as, for example, to cause the shirring to take place continuously, but to provide a greater amount of pucker at one point than at others. For this purpose, the position of the presser foot 6 is adjusted by means of the hand nut 62. This can also be accomplished by increasing the length of the stitch with the stitch adjustment with which every machine is provided.

When the presser foot 6 is lowered with respect to the sleeve 45 so that it comes closer into engagement with the base material, a smaller amount of shirring takes place. In order to provide a certain amount of shirring, as indicated at 134 (Figure 11) in spaces between the greater amount of shirring or puckering, as indicated at 135 (Figure 11), the presser foot 6 is adjusted so that in its lower position it does not exert a maximum pressure on the base material. In that case, a small amount of shirring takes place at all times but, when the presser foot is raised by the cam action above described, a maximum amount of shirring or puckering takes place. It is obvious that by changing the throw of the presser foot 6 any desired relation will be obtained between the sections of maximum and minimum shirring. In some instances, the attachment may be such that normal shirring is produced alternately with large puckers or gatherers in the material.

When the base material is fed through the edge folder 51, the edge is rolled or folded to

- form folds 137 (Figures 8 and 9). It is passed to the machine and stitched in this form, a stitch 136 extending through the folds 137 of the base material and also securing the shirring thereto.
- 5 If the shirring is to be applied to the base material at a point other than at the edge thereof, the base material is not fed through the edge folder 51 but is extended thereover so as to properly align the same to receive the shirring, as indicated in Figure 10. It is obvious that the base material may be extended any desired distance above and below the shirring in this manner.

15 In some instances it may be desired to make the shirring independently of the base material. For this purpose the base material is omitted and the device is operated with the shirring material only. The different rates of speed produced by the presser foot 6 and the auxiliary presser foot 40 cause the material to pucker or gather as above described and to be stitched in that form. The shirring thus made can be attached to a base material or to a garment in the usual manner.

25 From the above it is to be noted that an intermittent shirring is automatically produced having the desired characteristics and that the attachment may be readily applied to or removed from a standard sewing machine in a few minutes time without requiring any drilling or changes in the machine, the standard drilled holes being used for this purpose.

30 Although a particular embodiment of the invention has been described for purposes of illustration, it is obvious that various changes and modifications may be made therein without departing from the broad aspects thereof. The invention is to be limited only in accordance with the following claims when interpreted in view of 40 the prior art.

I claim:

1. In a sewing machine a feed dog, a main presser foot adapted to control the rate of feed of material thereby, an auxiliary presser foot co-45 operating with a portion of the feeding dog independently of the main presser foot, drive means for said machine, and means operable by said drive means to periodically vary the pressure of said main presser foot on the material so as to 50 alter the characteristics of the stitched product.

2. In a sewing machine a feed dog, a main presser foot adapted to control the rate of feed of material thereby, an auxiliary presser foot co-operating with a portion of the feeding dog independently of the main presser foot, drive means for said machine, and means operable by said drive means to periodically raise and lower said main presser foot so as to alter the characteristics of the stitched product.

60 3. In a sewing machine a feed dog, a main presser foot adapted to control the rate of feed of material thereby, an auxiliary presser foot co-operating with a portion of the feeding dog independently of the main presser foot, drive means for said machine, and cam means operable by said drive means to periodically vary the pressure of said main presser foot on the material so as to alter the characteristics of the stitched product.

4. In a sewing machine a feed dog, a main 70 presser foot adapted to control the rate of feed of material thereby, an auxiliary presser foot co-operating with a portion of the feeding dog independently of the main presser foot, drive means for said machine, and a rotatable cam operated by said drive means to vary the pressure of said

main presser foot on the material so as to alter the characteristics of the stitched product.

5. In a sewing machine a feed dog, a main presser foot adapted to control the rate of feed of material thereby, an auxiliary presser foot co-operating with a portion of the feeding dog independently of the main presser foot, a rotating drive means for said machine, a cam disk operated thereby at a slower speed, and means actuated by said cam disk for periodically varying the pressure of said main presser foot on the material so as to alter the characteristics of the stitched product.

6. In a sewing machine a feed dog, a presser foot adapted to control the rate of feed of material thereby, a rotating drive means for said machine, a cam disk, a reciprocating arm adapted to drive said cam disk in one direction, eccentric means operating said arm from said rotating drive means, and means actuated by said cam disk for periodically varying the pressure of said presser foot on the material so as to alter the characteristics of the stitched product.

7. In a sewing machine a feed dog, a presser foot adapted to control the rate of feed of material thereby, a rotating drive means for said machine, a cam disk, a reciprocating arm adapted to drive said cam disk in one direction, eccentric means operating said arm from said rotating drive means, means to adjust the throw of said arm for changing the speed of rotation of said cam disk, and means actuated by said cam disk for periodically varying the pressure of said presser foot on the material so as to alter the characteristics of the stitched product.

8. In a sewing machine a feed dog, a presser foot adapted to control the rate of feed of material thereby, drive means for said machine, and a rotatable cam operated by said drive means to vary the pressure of said presser foot on the material, and means to adjust the speed of rotation of said cam with respect to the speed of said drive means so as to alter the characteristics of the stitched product.

9. In a sewing machine a feed dog, a presser foot adapted to control the rate of feed of material thereby, a rotating drive means for said machine, a cam disk having a friction drum associated therewith, a reciprocating arm having friction ratchet mechanism adapted to engage said drum for driving the same in one direction, eccentric means operating said arm from said rotating drive means, and means actuated by said cam disk for periodically varying the pressure of said presser foot on the material so as to alter the characteristics of the stitched product.

10. In a sewing machine having a presser foot, feed dogs, and driving mechanism, a shirring device having means to guide shirring material to the feed dogs independently of said presser foot, means to feed a base material to said presser foot, and means to periodically vary the pressure of said presser foot on said base material for altering the rate of feed thereof so as to change the characteristics of the shirring.

11. In a sewing machine having a presser foot, feed dogs, and driving mechanism, a shirring device having means to guide shirring material to the feed dogs independently of said presser foot, means to feed a base material to said presser foot, and means to periodically raise and lower said presser foot on said base material for altering the rate of feed thereof so as to change the characteristics of the shirring.

12. In a sewing machine having a presser foot, 75

feed dogs and driving mechanism, a stirring device having means to guide stirring material to the feed dogs independently of said presser foot, means to feed a base material to said presser foot, and means to periodically raise the presser foot from said base material so as to retard the feed thereof and to increase the puckering or stirring of the stirring material.

13. In a sewing machine having a presser foot, feed dogs, and driving mechanism, a stirring device having means to guide stirring material to the feed dogs independently of said presser foot, means to feed a base material to said presser foot, and means to periodically vary the pressure of said presser foot on said base material for altering the rate of feed thereof so as to produce intermittent stirring.

14. In a sewing machine having a presser foot, feed dogs, and driving mechanism, a stirring device having means to guide stirring material to the feed dogs independently of said presser foot, means to feed a base material to said presser foot, and means to periodically vary the pressure of said presser foot on said base material for altering the rate of feed thereof so as to cause inter-

mittent changes in the amount of pucker or stirring.

15. In a sewing machine a feed dog, a presser foot adapted to control the rate of feed of material thereby, drive means for said machine and a rotatable cam operated by said drive means to control the raising and lowering of said presser foot to vary the pressure of said presser foot on said material, said cam having means to vary the effective length of the surface thereof to change the relative times for raising and lowering said presser foot.

16. In a sewing machine a feed dog, a main presser foot adapted to control the rate of feed of material thereby, an auxiliary presser foot 15 cooperating with a portion of the feed dog independently of the main presser foot, drive means for said machine and a rotatable cam operated by said drive means to control the raising and lowering of said presser foot to vary the pressure of 20 said presser foot on said material, said cam having means to vary the effective length of the surface thereof to change the relative times for raising and lowering said presser foot.

CHARLES SEAMAN. 25
